INDOOR TELEVISION ANTENNA OR SIMILAR ARTICLE

Gerson Snyder, Philadelphia, and Charles R. Margolies,
Oreland, Pa., assignors to Snyder Manufacturing Com-
pany, Philadelphia, Pa., a corporation of Pennsylvania

Filed Sept. 16, 1969, Ser. No. 19,171

Term of patent 7 years

Int. Cl. D14—99

U.S. Cl. D26—14

FIG. 2.

FIG. 1.

FIG. 3.

FIG. 4.

FIG. 5.

FIG. 6.

FIG. 7.

FIG. 8.

FIG. 1 is a side elevational view of an indoor television antenna or similar article, showing our new design with two telescoping pivoted rod antenna elements;

FIG. 2 is a top plan view thereof, to a reduced scale;

FIG. 3 is a face view of the dial, to an enlarged scale, taken along line 3—3 of FIG. 1;

FIG. 4 is a face view of the dial similar to FIG. 3 with a portion of the dial broken away;

FIG. 5 is a fragmentary side elevational view thereof, to an enlarged scale, with a portion of the dial shown in section and broken away;

FIG. 6 is a front elevational view thereof with the antenna elements partially extended;

FIG. 7 is a rear elevational view thereof, to a reduced scale, with portions of the antenna elements broken away;

FIG. 8 is a bottom plan view thereof, to a reduced scale.

We claim:

The ornamental design for an indoor television antenna or similar article, as shown and described.
